MAGNETIC GAME TABLE

Marjorie M. Kim, San Diego, Calif., assignor to Wilford Cruz, Fullerton, Calif.

Filed Aug. 3, 1970, Ser. No. 24,282

Term of patent 14 years

Int. Cl. D21—00
U.S. Cl. D34—5

Fig. 1

APR 11 1972

Fig. 2

Fig. 3

Fig. 4

FIG. 1 is a plan view of a magnetic game table showing my new design;

FIG. 2 is a side elevation view thereof;

FIG. 3 is a front elevation view thereof; and

FIG. 4 is a cross-sectional view thereof, taken along the line 4—4 in FIG. 1.

The shelf below the table is plain and unornamented.

I claim:

The ornamental design for a magnetic game table, as shown and described.
